UNITED STATES PATENT OFFICE

102,289

DESIGN FOR A COMBINED CLOCK FACE, WEATHER AND TEMPERATURE INDICATOR

Max M. Pochapin, New York, N. Y.

Application September 10, 1936, Serial No. 64,791

Term of patent 7 years

To all whom it may concern:

Be it known that I, Max M. Pochapin, a citizen of the United States, residing at New York city, in the county and State of New York, have invented a new, original, and ornamental Design for a Combined Clock Face, Weather and Temperature Indicator, of which the following is a specification; reference being had to the accompanying drawing, forming a part thereof.

Fig. 1 is a plan view of a combined clock face,

weather and temperature indicator, showing my new design.

Fig. 2 is a top view looking downwardly on Fig. 1.

I claim:

The ornamental design for a combined clock face, weather and temperature indicator, as shown.

MAX M. POCHAPIN.
